UNITED STATES PATENT OFFICE.

MARION ELIZABETH DEAN, OF TAUNTON, MASSACHUSETTS.

TATTING-SHUTTLE.

1,401,053.

Specification of Letters Patent. Patented Dec. 20, 1921.

Application filed March 10, 1920. Serial No. 364,724.

To all whom it may concern:

Be it known that I, MARION E. DEAN, a citizen of the United States, residing at Taunton, in the county of Bristol and State 5 of Massachusetts, have invented certain new and useful Improvements in Tatting-Shuttles, of which the following is a specification.

My invention relates to an improvement in tatting shuttles.

10 Tatting is extremely slow work and anything which shortens the amount of work is advantageous. The present shuttle shortens the work and increases the speed of tatting tremendously and it consists in a shuttle having one of its points extending beyond the end of its fellow and this extended point has a transverse groove near the end the function of which is to stay the thread after it is picked up, this method 15 being much better than the pick form by extending the shuttle as heretofore, which has been known to rip the finger of the operator who tats constantly and consequently the shuttle having an extended pick is soon dis- 20 carded for the further reason that it interferes with the regular tatting motion and in order to avoid the pick on such a shuttle, after it has made the fingers sore, the one who tats tries to direct the shuttle in a 25 foreign direction to avoid the contact with the pick and thus the speed is lessened whereas with my present invention these objections are entirely overcome and the speed of tatting is greatly increased.

30 This invention includes a combination of the ordinary time honored tatting shuttle with a crochet hook and can be used for tatting and eliminates the necessity of using a crochet hook or a pin now commonly em- 35 ployed in connection with the ordinary shuttle, the present invention enables the operator to do all that is necessary in the tatting operation with a single instrument.

In the accompanying drawings—

40 Figure 1, is a view in elevation.

Fig. 2, is a longitudinal sectional view.

45 Fig. 3, is a sectional view of a detail of the shuttle point.

The numerals 1 and 2, represent the two main members of a tatting shuttle separated by the spacing block 3, around which thread is wound in the usual manner. One end 4, 50 of the tatting shuttle is preferably of ordinary form whereas the opposite end 5, one member is shortened and rounded, and 55 the adjacent end 6, of the other member projects there beyond and is provided with a transverse V-shaped groove 7, as shown in Fig. 2.

While either end might be used for tatting, the end 4, would probably be used in the ordinary tatting operation, whereas when it is desired to stay the thread after it shall have been picked up, the end 6, with the groove 7, is employed to accomplish this. 60 This one instrument is used to do the entire work of tatting thus saving many motions of the hands and consequently a great amount of time in the tatting operation and at the same time obviating the difficulties mentioned in the use of a tatting shuttle having an extended pick.

I claim,

A tatting shuttle including two members secured together with inwardly extending spring ends, three of which are tapering and one rounded and shorter than the adjacent end, said projecting adjacent end having a transverse groove thereacross sunk in the body of the metal close to but removed 80 from the end thereof, the metal of said end being of substantially the same thickness on both sides of said groove, thus maintaining a plain surface and the external surfaces of 85 both members being smooth and free from obstructions, the whole so arranged that either end of said shuttle may be used for tatting without fear of catching the thread at undesirable times and yet so that when desired the thread may be stayed by said 90 groove.

In testimony whereof I affix my signature.

MARION ELIZABETH DEAN.
